KARL VÖLLER, OF DUSSELDORF, GERMANY, ASSIGNOR TO RHEINISCHE METALLWAREN-
UND MASCHINENFABRIK, OF DUSSELDORF-DERENDFORD, GERMANY.

AUTOMATIC FIRING MECHANISM.

No. 887,713.

Specification of Letters Patent. Patented May 12, 1908.

Application filed January 14, 1907. Serial No. 352,164.

To all whom it may concern:

Be it known that I, KARL VÖLLER, engineer, a subject of the German Emperor, residing at Dusseldorf, 17 Jülicherstrasse, German, have invented certain new and useful Improvements in Automatic Firing Mechanism; and I do hereby declare the following to be a full, clear, and exact description of the invention, such as will enable others skilled in the art to which it appertains to make and use the same.

This invention relates to a device by which a gun is automatically fired as soon as the breech is closed. By the act of closing the breech the trigger device is so moved that the release of the firing bolt or hammer occurs as soon as the closing movement is finished.

The device is preferably so arranged that in the event of a misfire the trigger device can be actuated by hand without the necessity for again opening the breech.

Two embodiments of the invention are illustrated in the accompanying drawings.

Figure 1 is a side elevation of one modification. Fig. 2 is a sectional plan in which the parts are in the position that they have at the moment of firing. Fig. 3 is a sectional plan showing the parts in the position which they have after firing. Fig. 4 is a sectional plan showing the position of the parts at the beginning of the movement of the sear for firing. Fig. 5 is a modification in horizontal longitudinal section showing the parts in the position which they have when the firing can be performed by hand. Fig. 6 is a detail view of the sear. Fig. 7 shows the position of the parts when the firing is automatic. Fig. 8 is a longitudinal section through Fig. 1 showing the connection between the trigger device and the firing pin.

Referring to Figs. 1-4, the breech closing wedge *a* is pushed into position by actuating the handle or lever *b* by hand in the known manner. As soon as the wedge is in the position indicated in dotted lines in Fig. 4, that is when it still has to move through the distance *x* in order to become fully closed, a sliding piece *c* in the lever *b* strikes against an arm *d* mounted on a pin *e* which is journaled in the breech of the gun. When the lever *b* is moved further inwards towards the axis of the barrel and the wedge is thus brought into the fully closed position, the sliding piece *c* turns the arm *d* and its pin *e* until the arm is

in the position shown in Fig. 2. The pin *e* carries a second arm *f* which, when the arm *d* is turned as aforesaid, is itself turned outwards and thus presses in the same direction the sear *g* pivoted in the wedge until the sear has the position shown in Fig. 2. In pushing the wedge fully home, the sliding piece *c* has been pushed so far to the left that the arm *d* becomes disengaged from the point of the sliding piece *c*, this movement of the latter to the left being due to the engagement of a pin *h* which it carries in an inclined slot *k* in the wedge. The pressing back of the sear by means of the arm *f* releases the firing bolt and fires the gun. As soon as the arm *d* has disengaged itself from the sliding piece *c*, the sear *g* is turned back into the normal position as shown in Fig. 3, by the torsion of the spring *i* surrounding its pivot.

Should the automatic action fail, the sear *g* can be drawn back from the position shown in Fig. 3 into the position shown in Fig. 2 by grasping the handle *k* for firing by hand.

The automatic firing device can easily be put out of action by removing either the sliding piece *c* or the lever *f* from the breech, or by disengaging the pin carried by the sliding piece *c* from the slot *h* and withdrawing the sliding piece.

In Figs. 5-7 a bolt *l* is rotatably mounted on the gun barrel to act as a stop. This bolt extends into a cavity in the sear *o* and has a lateral projection *m* which enters a groove *n* in the side of the said cavity, this groove being extended as an annular groove around the closed end of the cavity.

In the position shown in Fig. 5 in which the sear is fully home over the bolt *l*, the latter can be turned by a handle *q* through an angle of 90°, so that the projection *m* passes into the annular extension of the groove *n* and thus prevents the sear from being drawn backwards. If the bolt *l* is turned into the last mentioned position when the wedge is not fully home, the sear *o* will be prevented from moving home when the lever *b* (Fig. 1) is moved to fully close the breech, this position of the parts being shown in Fig. 7.

The length of the bolt *l* is such that at the moment of fully closing the breech, the sear *o* is so far back that the firing bolt is released and the charge fired. Should a misfire occur in this construction, the bolt *l* is turned into the position in which its projection *m*

can enter the groove *n* in the sear *o* as shown in Fig. 5, so that by pulling the handle *p* the gun can be fired.

If it is desirable to throw the automatic firing device out of action, it is only necessary to leave the bolt *l* in the position shown in Fig. 5, so that the sear *o* will not be held back when the breech is closed.

The invention may also be applied to breeches having a screw closure.

Having now particularly described and ascertained the nature of my said invention and in what manner the same is to be performed, I declare that what I claim is:—

1. In an automatic firing device for guns, the combination, with the firing mechanism, a trigger to cock and release the same, and a breech closure, of means automatically actuated simultaneously with the final breech closing movement to operate the trigger to cock and release the firing mechanism, said trigger being also operable independently of the breech closure in case of misfire.

2. In an automatic firing device for guns, the combination, with a breech block, of means to close the same, a trigger separate from the breech closing means to cock and release the firing mechanism, and means arranged to be brought into action automatically by the final closing movement of the breech to operate the trigger to fire the gun.

3. In an automatic firing device for guns, the combination, of a breech block, a breech closing handle, a trigger to cock and release the firing mechanism arranged to be operable independently of the handle, and means actuated by the final closing movement of the handle to operate the trigger to fire the gun.

4. In an automatic firing device for guns, the combination, of a breech block, a breech closing handle, a sear, and a two-armed lever arranged with one arm in contact with the sear and the other in the path of the final closing movement of the handle, whereby the gun is automatically fired upon the completion of the breech closing movement.

5. In an automatic firing device for guns, the combination, of a breech closing handle, a sear separate from the handle and arranged to cock and release the firing mechanism, a

two-armed lever arranged with one arm in contact with the sear and the other in the path of the final closing movement of the handle, whereby the gun is automatically fired upon the completion of the breech closing movement and in case of misfire the firing mechanism may be cocked and again released without opening the breech.

6. In an automatic firing device for guns, the combination, of a breech block, a breech closing handle, a sear, and a two-armed lever arranged with one arm in contact with the sear and the other in the path of the final closing movement of the handle, a detent carried by the handle and arranged to engage one arm of the lever, and means to retract the detent to release the lever and sear, whereby the gun is automatically fired and the sear returned to its normal position upon the completion of the breech closing movement.

7. In an automatic firing device for guns, the combination, of a breech block, a breech closing handle, a sear separate from the handle to cock and release the firing mechanism, a two-armed lever arranged with one arm opposite the sear and the other arm in the path of the final closing movement of the handle, a detent mounted for sliding movement in a slot in the handle and arranged to engage one arm of the lever, a pin carried by the detent and arranged to ride upon an inclined surface to retract the detent to release the lever, and means to return the sear to its normal position when the lever is released, whereby the gun is automatically fired upon the completion of the breech closing movement and the sear then returned to its normal position, and whereby in case of misfire the sear may be operated by hand to cock and release the firing mechanism without again reopening the breech.

In testimony whereof I have hereunto affixed my signature in the presence of two witnesses.

KARL VÖLLER.
